SHEET FEEDING APPARATUS

Filed July 7, 1930

FIG. 2

UNITED STATES PATENT OFFICE

2,049,112

SHEET FEEDING APPARATUS

Ray M. Fenton, Youngstown, Ohio, assignor to
 The Newton Steel Company, Youngstown, Ohio,
 a corporation of Ohio

Application July 7, 1930, Serial No. 466,148

7 Claims. (Cl. 80—44)

This invention, relating as indicated to sheet feeding and conveying apparatus, has specific reference to apparatus adapted to be employed for the purpose of feeding sheets to a pair of 5 rolling mill rolls, such sheets being received either from a second pair of rolling mill rolls, or from any form of apparatus usually employed in the manufacture of sheet iron. More specifically my invention relates to a sheet feeding apparatus 10 adapted to be employed in connection with cold rolls which are usually employed for the purpose of finishing sheets after the same have been preliminarily rolled in the usual hot mills. Considerable difficulty has been experienced in the 15 past in sheet metal practice in feeding the sheets which are usually arranged in packs to the cold rolls so that such sheets are not broken, split, or marred in being fed to the rolls and in their passage therethrough.

20 When a pack of sheets is fed from a horizontal plane directly into the cold roll mill, such sheets will have a tendency to whip both vertically and laterally, which usually results in damage to a number of such sheets. As a direct result of each 25 whipping, and also the sheets having a tendency to spread in passing into the cold roll, a marking or defacing of such sheets occurs when the same pass into the neck or unpolished terminals of the rolls. The only means heretofore success- 30 fully employed for the purpose of preventing a whipping or spreading of the sheets in the pack as fed to the cold roll has been to manually feed such sheets in order to obviate the formation of a considerable quantity of scrap. The manual 35 feeding of the sheets is, however, undesirable from the standpoint of the cost, as well as the slowing down of production incidental to the injection of the human element in the line of production. It is among the objects of my invention to provide 40 a sheet feeding apparatus which shall have none of the above named undesirable characteristics and further which may be employed not only to speed up production and reduce the cost of manu- 45 facture, but also to materially reduce the formation of scrap.

Other objects of my invention will appear as the description proceeds. To the accomplishment of the foregoing and related ends, said invention, then, consists of the means hereinafter fully described and particularly pointed out in the claims.

The annexed drawing and the following description set forth in detail certain mechanism 55 embodying the invention, such disclosed means constituting, however, but one of various mechanical forms in which the principle of the invention may be used.

In said annexed drawing:

Fig. 1 is a part-sectional, part side elevational

view of the apparatus comprising my invention; and Fig. 2 is a fragmentary plan view of the apparatus illustrated in Fig. 1.

Referring more specifically to the drawing, the apparatus comprising my invention is shown positioned intermediately of two pairs of rolling mill rolls 1 and 2, 3 and 4. The preferred direction of travel of the sheets through the apparatus is from rolls 3 and 4 to the rolls 1 and 2. The upper roll 2 of the last named pair of mill rolls has 10 associated therewith a pinch roll 5 which preferably runs in contact with the upper of such rolls and which may be journalled in the housing in which the mill rolls are journalled or in any other suitable housing which will maintain such 15 pinch roll in proper relation to the mill rolls. No means of support for the pinch roll is illustrated in the drawing, it being understood that any one of a number of supporting means may be employed as is well known to those familiar with the 20 art of rolling mill construction.

Positioned intermediately of the two pairs of rolling mill rolls is the sheet conveying and feeding table forming a part of my invention, which consists of side frame members 6, 7, 8, and 25 9, which may be suitably supported upon legs 10, 11, 12, and 13. It will be noted that the side frame members 6 and 7 which are supported on the legs 10 and 11 are inclined as most clearly shown in Fig. 1 for the purpose hereinafter more 30 fully explained. The side frame members 6 and 7 have extending transversely thereof shafts 14 and 15, which are suitably journalled in bearings 16 and 17 mounted on such side frame members, and such shafts 14 and 15 have secured thereto 35 a plurality of wheels 18 and 19 which serve as a means of support and propulsion for a plurality of endless conveyor belts 20. Other idler shafts, such as 21, 22, 23 and 24, are suitably journalled in brackets mounted on the side frame members 40 6 and 7, the shafts 21, 22, and 23 being in the form of rollers for supporting the conveyor belts 20, while the shaft 24 has a plurality of wheels such as 19 secured thereto for the purpose of sustaining such endless conveyor belts in passing 45 around the end of the feed table. It will be noted that some of the endless conveyor belts 20, namely those in the center of the table, extend into close proximity with the mill rolls 1 and 2 while the side belts terminate at a short distance from such 50 rolls. This construction or arrangement of the belts permits the sheets to pass more freely from the end of the conveyor to the mill than would be possible were such side belts to extend into close proximity to the mill.

The side frame members 8 and 9 have extending transversely thereof and journalled thereon shafts 25 and 26, said shafts having a plurality of axially spaced rolls such as 19 secured thereon for the purpose of sustaining and propelling, a 60

second endless conveyor 27. The endless conveyor belts 27 pass around wheels such as 19 which are secured to a shaft 28 which may be journalled in bearing blocks mounted on bracket 5 members 29. The shaft 26 has a flexible coupling or other suitable form of coupling 30 associated therewith which is likewise secured to the shaft 31 of a motor 32 by means of which the conveyor is driven. The shafts 26 and 14 10 have sprocket wheels 33 and 34 mounted thereon, which sprocket wheels are encircled by a sprocket chain 35 which is employed to drive the shaft 14 from the shaft 26. The endless conveyor belts 27, more specifically the shaft 15 26 carrying the wheels 19, around which the left end of such conveyor belts travel, is positioned higher than the receiving end of the conveyor belts 20, namely the periphery of the wheels 18. By having the two conveyor belts arranged in 20 the above described manner, the sheets may pass easily from the conveyor 27 onto the conveyor 20 without becoming jammed in the break between such conveyors.

It will be noted that by employing the above 25 described sheet conveying and feeding apparatus, the sheets after they leave the rolls 3 and 4 are received on the horizontal conveyor 27 which moves the same onto the conveyor 20 which, as hereinbefore described has oppositely sloping portions 30 sloping away from the shaft 23. As the packs of sheets pass over the hump above the shaft 23, such packs of sheets will be bent so that when the front ends thereof pass into the mill rolls 1 and 2 any whipping action of such 35 sheets is entirely obviated. The breaking of the pack across the hump over the shaft 23 also prevents any spreading of the sheets in the pack which would occur were the sheets to remain dished or unbent as the same pass into the second pair of mill rolls.

It will be noted that, instead of introducing the sheets or packs of sheets directly into the rolls 1 and 2, such sheets are first engaged by the pinch roll 5 which likewise causes a bending or 45 breaking of the sheets so that all whipping or scattering of the pack is entirely eliminated.

With the above described form of construction, the sheet feeding and transporting is accomplished entirely automatically without the supervision of an operator and the feeding to the 50 second pair of rolls is accomplished in a manner much superior to that which could be accomplished by the employment of a manual control over the pack as it is fed to the rolls. It is believed that any further description is unnecessary for those familiar with the art of rolling mill construction; and such apparatus, although having been explained in connection with the feeding operation for cold rolls, may likewise 55 be employed for the purpose of feeding sheets either singly or in packs to any form of apparatus usually employed in the manufacture of sheet metal.

Other modes of applying the principle of my 60 invention may be employed instead of the one explained, change being made as regards the mechanism herein disclosed, provided the means stated by any of the following claims or the equivalent of such stated means be employed.

70 I therefore particularly point out and distinctly claim as my invention:

1. In combination with a pair of rolling mill rolls, a sheet feeding table adjacent said rolls, said feeding table including an endless conveyor having oppositely sloping portions respectively adapted to receive such sheets and feed the same to said rolls, and a second endless conveyor in longitudinal alignment with said first named conveyor, said last named conveyor having its discharge end at a greater elevation than the receiving end of said first named conveyor. 5

2. In combination with a pair of rolling mill rolls, a pinch roll associated with one of said mill rolls, and a sheet-feeding table including an endless conveyor adapted to deliver sheets onto a second endless conveyor, said last named conveyor comprising a plurality of parallel belts having oppositely sloping portions adapted to respectively receive the sheets and present the same to said pinch roll and mill roll, the lateral conveyor-belts terminating remote from the rolls. 10 15

3. In combination with rolling mills in tandem, endless conveyor means between said mills comprising a plurality of conveyor belts and a second plurality of conveyor belts having oppositely sloping portions adapted to respectively 25 receive such sheets from said first-named conveyor, the receiving end of said last-named conveyor being at a lower elevation than the discharge end of the said first-named conveyor.

4. In combination with rolling mills in tandem, endless conveyor means between said mills comprising a plurality of parallel conveyor belts and a second plurality of endless conveyor belts having oppositely sloping portions adapted to receive sheets from said first-named conveyor, the 30 central members of said second plurality of conveyor belts extending closely adjacent to the corresponding mill and the lateral members being shorter and spaced back from the mill. 35

5. Sheet feeding mechanism including an endless conveyor having oppositely sloping portions 40 respectively adapted to receive sheets and feed them to a pair of rolls, and a second endless conveyor in longitudinal alignment with said first-named conveyor, said last-named conveyor 45 having its discharge end at a greater elevation than the receiving end of said first-named conveyor.

6. Mechanism for feeding sheets to rolling mills including in tandem, endless conveyor means 50 comprising a plurality of conveyor belts and a second plurality of conveyor belts having oppositely sloping portions adapted to respectively receive the sheets from said first-named conveyor and feed them to a rolling mill, the receiving 55 end of said last-named conveyor being at a lower elevation than the discharge end of the said first-named conveyor.

7. The combination with a rolling mill for rolling relatively thin sheets, of a conveyor table adjacent said mill for feeding thereto the sheets to be rolled, said conveyor provided with adjacent oppositely sloping portions respectively extending to the receiving and discharging ends of the conveyor, said conveyor having a long continuous 60 upper surface and said adjacent sloping portions merging into a central curved surface lying above said adjacent portions so that a sheet passing over said conveyor to said mill is bent into angularly related portions. 65
